UNITED STATES PATENT OFFICE.

HARRY C. LEAMY, OF PHILADELPHIA, PENNSYLVANIA.

COMBINATION DAY BED AND EMBALMING BOARD.

Application filed October 5, 1926. Serial No. 139,689.

This invention relates to a combination day bed and a morticians' cooling or embalming board, and more particularly to a foldable bed frame structure, which is adapted to be used with a regulation embalming board to form a single unitary structure.

The principal object of the invention is to provide a foldable bed frame structure adapted to be set up about a regulation cooling or embalming board, to effect a natural bed like appearance and to minimize the suggestion of death, when a corpse is resting on the embalming board prior to placement in a burial casket.

15 A further object of the invention is to provide a combination bed and embalming board as specified, in which the bed frame is set up or assembled about a regulation embalming board in a manner adapted to form a bed surface of normal width, and wherein the top surface of the embalming board is flush therewith and the side edges of the embalming board in abutment with the inner parallel edges of the bed frame.

25 With these and other objects in view, the invention consists in the novel arrangement and features of construction hereinafter described and specifically defined in the claims hereunto appended.

30 Reference being had to the accompanying sheet of drawing forming a part of the specification, and wherein:

Figure 1 is a top plan view of the assembled bed frame, with a regulation embalming board positioned therein as indicated in dotted lines.

Figure 2 is a side elevational view of the bed frame, illustrating an embalming board as surrounded thereby.

40 Figure 3 is a cross sectional view through the assembled bed frame and embalming board, on the line 3—3 of Figure 1.

45 Referring more particularly to the drawing, the invention consists of a foldable bed frame generally indicated at 10, which comprises two end sections, the head piece 11, and the foot piece 12.

In order to connect the end sections 11, and 12, a pair of parallel side members 13, 50 are attached thereto, with the ends 14, thereof suitably provided with a button headed plate 15, with the button heads 16, projecting therefrom, adapted to be inserted in suitable slots 17, therefor which are formed in 55 an angle plate 18, secured to each end post

19, of the end sections 11, and 12, in the well known manner.

The parallel side members 13, each comprising two sections 20, and 21, of equal length, have their inner ends joined by 60 means of a hinge plate 22, mortised in and secured to the lower outer edge surface of the sections 20, and 21, as clearly shown in Figure 2.

65 The parallel side member forming sections 20, and 21, are each further provided with a hingedly connected rectangular section 23, adapted to normally extend inwardly and rest on the upper surface of the sections 20, and 21, with their outer edges flush with 70 said sections and disposed in a horizontal plane with the supporting surface of an embalming board, to form a relatively narrow and divided supporting ledge on each side of said bed frame for normally abutting 75 the major length side edges of an embalming board as indicated at A, and as clearly shown in Figure 3, of the drawing.

A pair of screw plates 24, having a short 80 stud 25, projecting at right angles from one side thereof, are adapted to be secured on the underside of and adjacent the outer corners of the rectangular sections 23, with the studs 25, therein, provided to be inserted in suitable apertures therefor, formed in a plurality of angle plates 26, secured to the major length side edges of the embalming board, with the free ends thereof extending laterally therefrom, adjacent the end corners of the embalming board, forming the 90 main center supporting surface of the bed structure when set up for use.

If it is so desired, a transverse aperture 95 27, may be provided adjacent the free end of the studs 25, for passing a suitable cotter pin or the like, carried by each of said screw plates 24, by means of a short section of chain, through the said transverse apertures 27, to prevent the disarrangement of the embalming board and bed frame connecting sections, when the structure is moved about or lifted from a given surface temporarily as a unitary structure.

100 From the foregoing description, taken in connection with the accompanying drawing, 105 it will be readily apparent to those skilled in the art, that I have provided a simple, practical, and efficient foldable bed frame for use in conjunction with a regulation embalming board, which is particularly adapt- 110

ed to give a pleasing appearance to an embalming board when set up, eliminate the ghastly appearance thereof when supporting a corpse, and which provides an inexpensive 5 method for transforming a regulation embalming board, into a day bed structure of standard width.

Having described my invention, what I 10 claim is:

- 10 1. The combination with a cooling board comprising a rectangular board having legs supporting it in a horizontal plane, of a folding bed frame comprising end sections and parallel side members therefor, means 15 for detachably assembling said end sections and side members about the embalming board, and hinged means carried by said side members for enclosing and abutting the side edges of said embalming board flush therewith.
- 20 2. The combination with a cooling board comprising a rectangular board having legs supporting it in a horizontal plane, of a foldable bed frame comprising end sections and 25 parallel side members therefor, means for detachably connecting said end sections and side members, foldable means associated with and hingedly carried by said side members normally in a lateral inwardly extending 30 position for enclosing and abutting the side edges of said embalming board flush therewith.
- 30 3. The combination with a cooling board comprising a rectangular board having legs supporting it in a horizontal plane, of a foldable bed frame comprising end sections and 35 parallel side members therefor, means for

detachably connecting said end sections and side members, foldable means associated with and hingedly carried by said side members normally in a laterally and inwardly extended position for enclosing and abutting the side edges of said embalming board flush therewith, and connecting means carried on the under side of said hinged means 40 and side edges of said board for maintaining said bed frame and board in adjusted assembled relation upon the placement thereof.

4. The combination with a cooling board 50 comprising a rectangular board having legs supporting it in a horizontal plane, of a foldable bed-forming frame comprising end sections and parallel side members therefor, means for detachably connecting said end 55 sections and side members, hinge means carried by said side members intermediate their ends to permit folding of said side members upon themselves, relatively narrow rectangular ledge sections hingedly connected to the outer upper edge of said side members and 60 normally adapted to rest thereon in a horizontal inwardly projecting manner for enclosing and abutting the parallel side edges of said embalming board flush therewith, 65 said ledge sections further adapted to increase the width of said embalming board, and connecting means disposed on the under-side of said ledge sections and side edges of said board for maintaining said bed and board in adjusted assembled relation upon moving or raising the same for placement.

In testimony whereof I affix my signature,
HARRY C. LEAMY.
